UNITED STATES PATENT OFFICE.

FRANZ JOSEF MÜLLER, OF FRANKFORT-ON-THE-MAIN, GERMANY.

TYPE-WRITER.

No. 921,270.

Specification of Letters Patent.

Patented May 11, 1909.

Application filed May 25, 1907. Serial No. 375,752.

To all whom it may concern:

Be it known that I, FRANZ JOSEF MÜLLER, citizen of German Empire, residing at Frankfort-on-the-Main, Germany, have invented 5 new and useful Improvements in Type-Writers, of which the following is a specification.

My present invention relates to a type-writer of the class which permits the printing 10 not only of types which occupy each the space of a single letter but, at pleasure, the printing of syllables or of types occupying a larger space than that of a single letter. The types may be provided in the machine 15 in various ways, either on an integral frame or on wheel sectors, each of the several letters being brought into printing position by the operation of a key. I prefer a construction where the three upper rows, which in- 20 clude the single characters, are disposed as customary in the typewriter systems heretofore in use, the said rows to be provided with a curved base and a similar printing surface while those rows where two or three 25 characters are to be printed by one operation are provided with small even surfaces, because the printing surfaces of two or three letters to be printed all at one time must not be curved, as in this case the middle portion 30 of each letter or the middle letter in a syllable would be printed stronger than the remainder or the side letters. To avoid this the printing frame is in those places where there are syllables or a plurality of characters 35 to be printed at one time, provided with small facets.

The drawing herewith shows constructions of a type frame as well as of the several parts of a machine, such as the operation of the 40 type frame, the hammer and so forth, the vertical space shifting of the carriage, all hereinbelow set forth.

Figure 1 is a vertical, longitudinal section through a typewriter provided with a parted 45 type frame, a vertically movable plate with printing apertures and a device for raising the entire type sectors and turning the sectors severally into printing position; Fig. 2 shows a plan view of Fig. 1; Fig. 3 is a vertical, 50 longitudinal section through part of a type writer of the class referred to provided with an integral type frame and a horizontally movable printing plate; Fig. 4 is a front view of the horizontally movable printing 55 plate; Fig. 5 is a perspective view of a ham- mer by means of which any types occupying a larger space than those for single letters may be brought to impression, the hammer adjusting itself automatically; Fig. 6 is a side view of the device shown in Fig. 5 with 60 the hammer as operating; Fig. 7 is a section through the shifting device of the carriage; Fig. 8 shows the limit of its vertical movement and Fig. 9 is a plan view of the shifting device.

The type frame as shown in Fig. 1 is composed of several sectors 1 which are with their hubs 2 severally mounted on a movable vertical axle 3 which has an annular enlargement 4 supported in the hub 5 of the plate 70 7 which is in turn carried by posts 6. To bring the several type rows of a frame in working position and height, that is at the level at which the impression of the type is made, there are provided beneath the respective key rows the balancing supports 8 (see Fig. 2) fulcrumed so as to move about a shaft 9 supported in blocks 10. The depression of one of the keys T and the simultaneous depression of one of the said supports 8 causes a rotatory movement of the shaft 11 which is likewise bearing in the block 10, such movement being by another balancing support lever 12 which is provided beneath and controlling all of the said supports 8, transmitted upon the lever 13, also secured on the shaft 11 and extending either below a hub of a lever 14, hereinafter referred to again, or beneath a catch in the main shaft 3, the type sectors 1 or the type frame being thereby 90 raised so far as to place the letter or syllable to be printed in the correct writing height. The fulcrums 2 and 11 being nearer to the keys (see Figs. 1 and 2 in which for want of space the device is shown crowded and the levers broken) the shaft 3 and therewith the type rows are always raised sufficiently to obtain a print therewith. To secure the adjustment of the several types or syllables of the sector, which is to be raised into the correct writing position by means of the proper rotatory movement of each of the several type-sectors the hub of each sector has a hollow extension 15 in which slides one of the rods 17 provided with a globular head 100 16, the latter engaging the middle member 18 of a triple-armed angular lever, the hub 19 of which turns on a vertical shaft secured in the bearings 20, the other arms 22 extending to both sides of the machine from the 110

type frame (see Fig. 2). On operating one of the keys of the first row the upmost type sector 1 will swing to the right or left and the respective letter appear just according to the 5 force of the operation or the position of the key, right or left or in the middle. On touching the second or any of the next following key rows all of the type sectors will by means of the aforesaid balancing supports 8 and 12 10 be raised at the same time. To permit this simultaneous raising the members 18 of the triple-armed angular levers are extensible, being composed each of two rods of which the upper is connected with the lower by 15 means of pins 23 sliding in a suitable slot.

The office of the rods 17 sliding in the extensions 15 is to permit the sectors to make outward strokes as they turn around the axle 3 while the arms 17 move only horizontally. By the interior springs 24 the said 20 angular levers 18, 22 are brought in horizontal position. The stroke of the keys T is regulated by the front board 25 provided for the purpose with notches of different lengths. 25 The key levers 26 are all fulcrumed in a shaft 28 mounted on supports 27.

To reduce the friction between the hubs 2 there may be provided ball bearings 29 between each two of the said hubs.

30 The key levers 26, the main office of which is to produce the rotatory movement of the several type sectors, have for a short distance a dead movement to avoid the depression of other key levers by the action of the triple 35 armed angular lever 18, 22, and which may also be employed for raising the type sectors to obtain a proper sequence of the several actions.

Close in front of the type frame there is 40 provided a sliding plate 30 which has several apertures of different sizes, each size corresponding respectively with the widths of the types of the type frame, so that either one or two letters or more letters, according to the 45 key operated, passes the respective aperture. The first three rows of keys operate those types which bear the letters or characters occupying each one space only and therefore, the aperture which has the size adapted 50 for the passage of one letter only will be required for the printing position while on operating a type of any of the other rows of the key board, which permit the printing at one time of two or three letters respectively 55 the aperture large enough for the passage of the respective number of characters should be in working position. To obtain the proper position of each aperture the plate 30 is vertically sliding in a frame 31 which may 60 be secured in any suitable way in the aforementioned plate 7, the said plate 30 being by its own weight constantly kept at such level that the aperture which corresponds with the respective character is in its required position, being moved by means of 65

the aforementioned lever 14 secured in the vertical axle 3 and rising with the sector 1. When the latter has been lifted far enough that two or three letters, respectively, are to be printed at one time the lever 14 has 70 correspondingly raised the plate 30 so that the aperture for the respective number of letters is in the required position.

In the typewriter represented in Figs. 3 and 4 the construction of the type frame is 75 different, the same being made of one integral piece instead of being composed of a plurality of independent sectors. There appears in this construction the disadvantage that when one of the types has been worn 80 out the entire frame has to be replaced while in the first described combination only one row of types need be exchanged. As, however, only the axle requires a rotatory movement, which may be brought about by means 85 of a toothed sector, a different operating device is to be employed. As shown in Figs. 3 and 4 the plate 30 may slide horizontally and the apertures 32 be disposed side by side to each other, the horizontal movement being 90 brought about by means of an inclined slot 33 in the plate 30 in which the lever 14 moves while raising the axle.

The printing of the types may be effectuated by one or more hammers. When more 95 hammers are employed they should be of different widths as the use of one or more letters at a time may require. They are operated in the known way shown in Fig. 3. The hammer 34 may, however, be made as 100 illustrated in Fig. 5, its disengagement being executed by any suitable means; it has three projecting pieces 35, 36, 37, each of the size of the space of a letter, the first piece 35, being rigid while the others, 36 and 37, are 105 rotatable on a pivot 38. There is further provided a bar 40 having a notch 39, the said bar being from the shaft 41 horizontally movable by means of a crank 42 in the stand 43.

When it is desired to print a single letter the pieces 44 and 45 projecting from the pieces 36 and 37 touch the bar 40 and are thereby tilted over as shown in Fig. 6. On the operation of a two-letter key the crank 115 42 moves through the rotatory movement of the vertical shaft 41 the bar 40 so much aside that the piece 44 passes the notch 39, the projecting piece 37 being tilted over as aforesaid. When a three-letter key is operated 120 the two pieces 44 and 45 pass the notch 39 so that the three pieces 35, 36, 37 are brought to action. After the operation all parts return to their normal positions, the pieces 36 and 37 being kept in the position shown in 125 Fig. 5 by means of suitable springs.

For the construction as shown in Fig. 3 a vertical shifting or spacing to adjust the carriage in vertical direction permitting the printing of capitals, figures and other char- 130

acters is provided. With the vertically and horizontally moving carriage is rigidly connected a groove 65 (Fig. 7), in which engages the roller 66 of the shift lever 67 (Fig. 7). To shift the carriage from the small-letter position to the middle or capital-letter position, the key 68 (Fig. 9) should be depressed which is by the cranks 70, 71 connected with a shaft 69 and mounted on the shaft 72, this construction transmitting the movement of the shaft 69 upon the shifting lever 67 (Figs. 7 and 9) which is thereby tilted and rises by means of the roller 66 of the carriage until the shifting lever touches with its left end the screw 37. By this way the lift of the carriage is exactly controlled. But when the carriage is to be brought to its upmost position, to be adapted for the printing of characters or figures, this may be done by operating the key 74 (Fig. 9). In this case the drawing rod 75 connected with the said key 74 draws forward the arm 76 so that the detent 73 which in Fig. 8 is on the opposite end of the arm 76 becomes withdrawn from beneath the adjusting lever 67 while the detent 77 arrives beneath the same. This permits of a deeper travel of the arm 67 with its left end and consequently to raise through the roller 56 the carriage to a correspondingly higher level. The key lever 74 is movably connected with the shaft 72. On releasing the key all parts return into their normal positions. By means of the catch 78 for the operation of the key 74 the key 68 is also depressed at the same time so that also by this way a rotatory movement of the shaft 72 may be obtained.

What I claim as new and desire to secure by a United States Letters Patent is:—

1. In a typewriter of the class where the keyboard comprises keys printing one, two or more characters at one time, the combination of horizontal wheel sectors mounted on a vertical axle, facets on the periphery of the said sectors adapted to bear types occupying a larger space each than a single letter, a grooved extension to the hub of each of the said sectors, a rod 17 having a globular end 16 sliding in each of the said extensions, a triple armed angular lever controlling the said rod, the arm 22 of the said lever being supported on an axle in a hanger suspended from a plate 7, a spiral spring 24 jointed to each of the said arms 22, keys adapted to act upon the said springs, a vertically and horizontally movable plate 30 in guides 31, apertures in the said plate 30 corresponding in size with the faces of the one-, two-, three-letter types, respectively, and disposed in correspondence with the corresponding keys. 40 45 50 55 60

2. In a type writer of the class described the combination of a hammer having a rigid piece and similar pieces which are yieldingly tilting and corresponding each in size with the width of a letter, catches emanating from the said pieces, a bar 40 vertically movable for distances corresponding with the widths of the one-, two-, three-letter types, a notch in the said bar, the said bar being within reach of the said catches. 65 70

In testimony whereof I have signed my name to this specification in the presence of two subscribing witnesses.
